UNITED STATES PATENT OFFICE.

HARVEY BIRCHARD TAYLOR, OF PHILADELPHIA, PENNSYLVANIA.

PUMPING SYSTEM.

1,231,310.

Specification of Letters Patent. Patented June 26, 1917.

Application filed September 29, 1914. Serial No. 864,046.

To all whom it may concern:

Be it known that I, HARVEY BIRCHARD TAYLOR, a citizen of the United States, residing at Philadelphia, in the county of 5 Philadelphia and State of Pennsylvania, have invented certain new and useful Improvements in Pumping Systems, of which the following is a full, clear, and exact specification.

10 This invention relates to pumping systems, and has particular reference to a multi-stage pump wherein it is desired to deliver relatively small volume of water against high head or pressure, or relatively large 15 volume of water against low head or pressure.

The invention is particularly adapted for pumps used on submarine vessels, which when near the surface may have to handle 20 large volumes of water under relatively low head, but which when submerged require the pumps to handle water against a greater head, but not necessarily in the same volume.

According to this invention, I accomplish 25 this result by modifying the connections between the several stages of a multi-stage pump by means of a novel valve mechanism especially adapted for the conditions in submarine vessels. An ordinary multi-stage 30 pump with the stages connected in series will discharge a relatively small amount of water against a high head, while by connecting the stages in parallel, a relatively large volume of water can be discharged against 35 a smaller head, with about the same consumption of power. But the problem is to devise a simple and reliable valve mechanism whereby the connections from series to parallel, or parallel to series, can be 40 quickly and easily made, and which valve mechanism will not require excessive space, or be objectionably heavy. In providing a valve mechanism which meets these conditions desired for pumps of submarine vessels, I have also devised a valve mechanism 45 whereby an intermediate volume of water can be handled against an intermediate head, by connecting the stages of a pump in series-parallel. This does not increase the 50 complexity of the valve mechanism, and provides an extremely elastic range of operation of the entire pumping system.

In the embodiment of the invention shown herein, there is provided in connection with 55 a multi-stage pump of a suitable design, si-

multaneously operable rotary valves, one controlling the connections on the suction sides of the several stages, and the other controlling the connections on the discharge sides of the several stages. At one position 60 of the rotary valves, the stages will be connected in series, for handling water against the maximum head. At another position the stages will be connected in parallel to handle the largest volume of water against 65 the minimum head, and at a third position the stages will be connected in series parallel to secure the intermediate condition. The valves are preferably interconnected by gearing controlled by a hand-wheel, so that 70 they will always be in proper relation to each other and to the several ports leading to and from the several stages.

In the accompanying drawings,

Figure 1 is a cross section through one 75 of the stages of a centrifugal pump with the valves in the series position, taken on the line 1-1 of Fig. 3;

Fig. 2 is a developed longitudinal section on the line A—B—C—D—E of Fig. 1; 80

Fig. 3 is a plan view;

Fig. 4 is a sectional view showing the valve connections for series parallel, and

Fig. 5 is a similar view showing the valve positions for parallel connection. 85

1 represents the casing of a centrifugal pump having four stages. 2 is a motor which drives the impeller shaft 3, 4 is the suction pipe and 5 a discharge pipe. The impeller shaft 3 passes through the usual stuffing box and bearings 6, 6, at both ends of the casing and is provided with a ball thrust bearing 7. The particular construction of the pump is not a part of this invention, but the pump shown is preferably a centrifugal pump of any desired number of stages, in which the impellers 8 are all mounted on the shaft 3, and comprise suitable moving vanes which co-act with stationary vanes 9. The vanes 9 are disposed between the periphery of the impellers 8 and the peripheral discharge chambers 10 of each stage. Each stage is also provided with an inlet chamber 11 which leads to the center of each impeller 8.

When the stages are connected in series, the water passing in at 4 flows through the inlet 11 of the first stage through the impeller 8 and the fixed vanes 9 to the discharge chamber 10 thereof, thence the water 110

- enters the inlet 11 of the next stage, and so on until it has passed through all of the stages and is discharged through the outlet 10 from the last stage into the discharge 5.
- 5 The work done by each stage is substantially equal, and the total head overcome is that due to the sum of the heads overcome by each stage, or the difference in head between the suction end 4 and the discharge end 5.
- 10 This position is illustrated in Fig. 2.
- The valve mechanism consists of a rotary multiple position inlet valve 15, and a similar outlet valve 16. These valves are respectively contained in casings 17, 18, symmetrically disposed below the pump casing 1. Each valve is carried by a separate shaft 19, 20, which carry gears 21, 22 meshing with an operating pinion 23. The operating pinion 23 is carried by a shaft 24, which 20 may be operated by a hand-wheel 25 or other suitable power.

- The inlet valve 15, see Figs. 1 and 2, consists of three longitudinal chambers 26, 27, 28, separated by a triple partition wall 29.
- 25 In Fig. 2, it will be seen that the inlet valve 15 is shown in vertical section on the line A—B, with the series inlet chamber 26 connected to the inlet 11 of the first pump stage through port 30. This port 30 is shown in 30 the dotted lines in Fig. 1, as it is behind the portion of the valve 15 through which the section of Fig. 1 is taken.

- The outlet valve 16 differs in detail from the inlet valve, as its functions are substantially the reverse of the inlet valve. The outlet valve 16 comprises intermediate series chambers 33, 33, 33, 34, which, in the positions of Figs. 1 and 2 connect the outlet chambers 10 of each stage with the inlet 40 chamber 11 of the succeeding stage, and the outlet 10 of the final stage is connected through port 34 with the discharge 5. Thus, the chamber 26 of the inlet valve 15 cooperates with the passages or ports 33, 34, 45 of the outlet valve 16 when the stages are connected in series.

- The outlet valve has a parallel discharge chamber 36 provided with a port 37 for each stage, so that when the parallel inlet 50 chamber 27 is in position so that its ports 38 communicate with the inlets 11, to the several stages, the outlet valve 16 is in position so that its ports 37 communicate with the outlets 10 from the several stages. Thus, 55 parallel operation of the stages is secured, and a large volume of water is handled at the head due to one stage. This position is shown in Fig. 5.

- To secure an intermediate volume of discharge, at an intermediate head the series 60 parallel arrangement of Fig. 4 is employed. The chamber 27 of inlet valve 15 is provided with a series port 40 which is angularly displaced from the parallel inlet ports 38, port 65 40 being in line with an additional series

port 41 in chamber 28. Thereby, the suction 4 is connected in parallel to the inlets 11 of, for example, the first and third stages of a four stage pump. At the same time, the outlet valve 16 is in such position that the 70 first and second stages are placed in series with each other by a passage 43 in outlet valve 16, and the third and fourth stages are also in series by a similar passage 44. At the same time, the discharge from stages 1 75 and 2 is connected to chamber 36 by passage 45 and that from stages 3 and 4 by passage 46. Thus the pressure is equal to twice that of one stage, and the volume handled is equal to twice the volume handled by one 80 stage, with this series parallel arrangement of stages.

It will be understood that the invention is not to be restricted to any particular type of pump, nor to any particular number of 85 stages, and it will be seen that with a greater number of stages not only could the extremes due to series and parallel connections of the stages be obtained, but by different series parallel groupings of intermediate stages more intermediate volumes and pressures could be obtained by properly designing the valves to give the desired groupings of stages. If the number of revolutions be assumed to be 1800, and the stages 90 be designed to give 200 gallons per minute against a head of 300 feet when in series, in parallel, at the same number of revolutions approximately 800 gallons per minute would be delivered against a head of 75 100 feet, and in series parallel approximately 400 gallons per minute are delivered against a head of 150 feet. With each of these arrangements and with the proper design of 105 pump, extremely efficient service will be secured, and the power required to operate the pump at the point of maximum efficiency for any of the several conditions does not greatly vary as the head and quantity inversely vary. The cylindrical interconnected valves disposed close to the pump casing and parallel to the pump shaft in the same 110 casing are especially advantageous by reason of their relatively small size for the results accomplished. It will be observed that the 115 valve chambers are of unequal volumes, those for the parallel flow being largest, and those for series flow smallest, while those for series parallel flow are of intermediate volume corresponding to the flow to be carried. Moreover, they are naturally approximately balanced against water pressure so that excessive power is not required to operate them even under heavy pressures.

While the invention is particularly useful 125 in a submarine vessel, it is useful in all other relations where it is desired to economically handle varying quantities of water or other fluids against varying heads.

Various modifications and changes may 130

- be made in the specific embodiment of the invention herein illustrated and described, without departing from the scope of the appended claims.
5. Having thus described my invention, what I declare as new and desire to secure by Letters Patent of the United States is:—
1. An inlet valve for a multi-stage pump comprising a hollow cylinder open at one end to receive the liquid, peripheral recesses to discharge said liquid, and an axial partition dividing said cylinder into separate passages for the entering fluid.
  2. A rotary valve for a multi-stage pump comprising a hollow cylinder open at one end and having peripheral recesses to pass the liquid, and an axial partition dividing said cylinder and said recesses into separate passages for the fluid.
  3. A valve for a multi-stage pump comprising a hollow cylinder open at one end and having peripheral ports to pass the liquid and separated longitudinal passages connecting said ports to the open end of the cylinder.
  4. A discharge valve for a multi-stage pump comprising a hollow cylinder open at one end and having peripheral ports to pass the fluid, and partitions for separating said ports into different combinations.
  5. A valve for a multi-stage pump comprising a hollow rotatable cylinder being open at one end and having peripheral ports and partitions separating said ports into groups.
  6. In a multi-stage pump, the combination with a plurality of impellers, of a casing therefor, an inlet valve common to said impellers and comprising a hollow cylinder receiving the fluid at its end and discharging it through peripheral ports, and a wall in said valve dividing it into longitudinal chambers to control the supply of said impellers in a plurality of combinations.
  7. In a multi-stage pump, the combination with a casing supporting a plurality of impellers and having inlet and exhaust passages therefor, of valve housings parallel to the axis of said impellers and having openings communicating with said inlet and exhaust passages, and valves in said housings controlling the flows through said impellers in a plurality of combinations and comprising open ended hollow cylindrical members receiving and discharging the entire inflow and outflow through the pump parallel to the axis of said impellers in all of said combinations.
  8. In a multi-stage pump, the combination of a series of stages, an impeller for each stage, a casing having a passage for each stage, a valve controlling said passages for grouping said stages in a plurality of combinations comprising a hollow movable cylinder having longitudinal chambers, and peripheral ports for each chamber coöperating with said casing passages to vary the connections between said stages, said chambers being connected to one end of said valve.
  9. In combination with a multi-stage pump, a rotary stage controlling valve having chambers varying in volume according to the flow to be controlled.
  10. In combination with a multi-stage pump, a rotary stage controlling valve having longitudinal chambers varying in volume according to the flow to be controlled.
  11. In a multi-stage pump, the combination with a longitudinal series of impellers, of a housing therefor having inlet and outlet passages for the flows through said impellers, cylindrical valve chambers having peripheral ports communicating with said passages and open at one end for passing the liquid, and movable valves in said chambers for controlling the flow through the impellers in a plurality of combinations and formed to connect all the flows to said open ends of said valve chambers in all of said combinations.
  12. In a multi-stage pump, the combination with a casing having three compartments substantially tangent to each other, of hollow rotary cylindrical valves in two of said compartments, driving wheels on the shafts of each of said valves and a central pinion engaging said wheels to rotate said valves.
  13. A pump comprising a series of centrifugal impellers, a substantially cylindrical casing for said impellers having inlet and exhaust passages at the sides thereof, open ended valve housings beneath, parallel with, and supporting said impeller casing and having openings communicating with the inlet and exhaust passages of the impeller casing, open ended valves in said housings adapted to receive the entire inflow of liquid through the open end of one valve housing, to control the flows through the impellers in a plurality of combinations and to discharge the entire outflow at an open end of the other valve housing.
  14. A pump comprising a series of centrifugal impellers, a substantially cylindrical casing for said impellers cast in two parts consisting of an integral base portion having inlet and exhaust passages at the sides thereof for the impellers and an integral cap portion mating with said base portion to form a housing for all of said impellers, open ended valve housings beneath, parallel with, and supporting said impeller casing and having openings communicating with the inlet and exhaust passages of the impeller casing, open ended valves in said housings adapted to receive the entire inflow of liquid through the open end of one valve housing, to control the flows through the impellers in a plurality of combinations and to discharge the

entire out-flow at an open end of the other valve housing.

15. A pump comprising a series of centrifugal impellers, a substantially cylindrical casing for said impellers cast in two parts consisting of an integral base portion having inlet and exhaust passages at the sides thereof for the impellers and an integral cap casting mating with said base portion to 10 form a housing for all of said impellers, open ended valve housings beneath, parallel with, and supporting said impeller casing and having openings communicating with the inlet and exhaust passages of the impeller casing, at least one of said housings being cast integral with said base portion of the impeller casing, open ended valves in 15 said housings adapted to receive the entire inflow of liquid through the open end of one valve housing, to control the flows through the impellers in a plurality of combinations and to discharge the entire outflow at an open end of the other valve housing.

16. A pump adapted to handle large quantities of water against a varying head and 25 comprising a series of centrifugal impellers on a common shaft, inlet and exhaust valves parallel to said shaft for controlling the flows through said impellers in a plurality of combinations, and a casing for said impellers and valves having inlet and exhaust 30 passages and consisting of an upper impeller housing having a lower integral base portion for all of said impellers and an integral cap portion mating therewith, and lower 35 cylindrical valve housings substantially tangent to each other and tangent to and integral with said base portion of the impeller housing.

In testimony whereof I affix my signature, 40 in presence of two witnesses.
